The ornamental design for a ceiling fan blade iron, as shown and described.

DESCRIPTION

FIG. 1 is a bottom perspective view of a ceiling fan blade iron in the environment of a ceiling fan;

FIG. 2 is another bottom perspective view of the ceiling fan blade iron of FIG. 1;

FIG. 3 is a front view of the ceiling fan blade iron of FIG. 1;

FIG. 4 is a rear view of the ceiling fan blade iron of FIG. 1;

FIG. 5 is a right side view of the ceiling fan blade iron of FIG. 1;

FIG. 6 is a left side view of the ceiling fan blade iron of FIG. 1;

FIG. 7 is a top view of the ceiling fan blade iron of FIG. 1; and,

FIG. 8 is a bottom view of the ceiling fan blade iron of FIG. 1.

In FIG. 1, the broken line directly adjacent and to the right side of shaded areas depicts portions of the ceiling fan blade iron. All other broken lines in FIG. 1 depict environmental subject matter. In FIGS. 2 through 8, all broken lines depict portions of the ceiling fan blade iron. All broken lines form no part of the claimed design.
